UNITED STATES PATENT OFFICE.

PHILIP NURSE, OF NEW YORK, N. Y.

HORSESHOE CALK AND CARRIER.

1,074,450.

Specification of Letters Patent. Patented Sept. 30, 1913.

Application filed February 28, 1913. Serial No. 751,285.

To all whom it may concern:

Be it known that I, PHILIP NURSE, a citizen of the United States, and a resident of the city of New York, borough of Manhattan, in the county and State of New York, have invented a new and Improved Horseshoe Calk and Carrier, of which the following is a full, clear, and exact description.

My invention has for its object to provide 10 a calk, having a curved plate with teeth adapted to be disposed against the inner side of a horse shoe, this curved plate having slots in which are disposed angular members, which extend upward at the outer sides 15 of the horse shoe, and are provided with openings at their upper terminals, through which may be disposed a strap for securing the calks in position. This curved plate with the teeth may be provided with inwardly disposed flanges, to which may be secured a pad.

Additional objects of the invention will appear in the following complete specification, in which the preferred form of the invention is disclosed.

25 In the drawings similar characters of reference indicate corresponding parts in all the views, in which—

Figure 1 is a side elevation of my calk and carrier showing how it is held in position 30 on the horse's hoof; Fig. 2 is a sectional elevation showing a modified form of the invention; Fig. 3 is an inverted plan view of Fig. 1; and Fig. 4 is an inverted plan view of Fig. 2.

35 By referring to the drawings it will be seen that a curved rib or plate 5 is provided, which is normally disposed against the inner side 6 of the horse shoe 7, this curved rib or plate 5 merely having sufficient thickness 40 to permit of the construction of the teeth 8 at its sides, the central portion of the toe 9 of the curved rib being sharpened as shown in the drawings. This curved rib 5 has horizontal slots 10, one at each side, there being 45 also a horizontal slot 11 in the toe or central portion 9 of the curved rib 5. In the slots 10 there are disposed portions 12, of the angular members 13, the portions 12 at the inner side of the curved rib 5 having depending flanges 14. These angular members 50 13 also have transverse teeth 13^a. Through the horizontal opening 11 there is disposed a portion 15 of the angular member 16, this portion 15 of said angular member 16 having a depending flange 17 disposed at the inner side of the curved rib 5.

The portions 12 of the angular members 13 extend outwardly under the horse shoe 7, and then upwardly at 19, as shown in Fig. 1 of the drawings, the upper portions 20 of 60 the angular members 13 having obliquely disposed slots 21. The portion 15 of the angular member 16 extends outward from the toe 9 of the curved rib 5, under the toe of the horse shoe. This angular member 16 65 has a portion 22, extending inward at the front of the horse shoe 7 and then rearwardly at 23, where it has a loop 24. A strap 25 is disposed through this loop 24, and then outwardly through the slots 21, the 70 portion 26 of the strap 25 being disposed against the hoof 27 of the horse, the calk being secured to the horse's hoof in this manner. From the loop 24 the angular member 16 extends downward at 16^a forming the 75 tooth 16^b at the front of the curved band 5. This form of the invention may be used with a pad 5^a as shown.

In the modified form of the invention shown in Fig. 2 of the drawings the curved 80 rib 5 has an inwardly disposed flange 28, extending rearwardly from its toe 9, and flanges 29 and 30 extending inwardly from its sides. A pad member 31 is disposed between the flanges 28, 29 and 30 of the horse's 85 hoof, this pad member 31 having a central opening 32. There is also a second pad member 33, which is secured at the bottom of the flanges 28, 29 and 30. The pad members 31 and 33 are secured to the flanges 28, 90 29 and 30 by the bolts 34.

In addition pad members 35 are disposed at the rear of the pad member 33, and between the rear terminals 36 of the curved rib, these pad members 35 being secured to 95 the pad members 31 and 33 by means of the rivets 37. In other respects the form of invention shown in Figs. 2 and 4 of the drawings conforms with the construction shown in Figs. 1 and 3 of the drawings.

Having thus described my invention I claim as new and desire to secure by Letters Patent:

1. In a horse shoe calk and carrier, a curved plate with teeth for engaging the 105 ground, and adapted to be disposed at the inner side of a horse shoe, there being openings in the plate, angular members disposed in the openings and normally extending upward at the outer side of the horse shoe, 110 there being openings in the upper ends of the angular members, and a strap disposed in

the second-mentioned openings for the purpose specified.

2. In a horse shoe cork and carrier, a curved rib adapted to be disposed in the inner side of the horse shoe, there being openings in the rib, angular members disposed in the openings and normally extending upward at the outer side of the horse shoe and vertically at the inner side of the curved rib, there being openings in the upper ends of the angular members, and a strap disposed in the second-mentioned openings for the purpose specified.

3. In a horse shoe cork and carrier, a curved rib adapted to be disposed against the inner side of a horse shoe, there being openings in the curved rib, angular members having portions extending through the openings in the curved rib, the said portions of the angular members having depending flanges at the inner sides of the curved rib, the angular members having upwardly extending terminals normally disposed at the outer side of a horse shoe, and means for engaging the terminals for the purpose specified.

4. In a horse shoe cork and carrier, a curved rib adapted to be disposed against the inner side of a horse shoe having teeth for engaging the ground, there being openings in the curved rib, angular members having portions extending through the openings in the curved rib, and vertically in the inner side of the curved rib, the angular members having upwardly extending terminals normally disposed at the outer side of the horse shoe, and means for engaging the terminals for the purpose specified.

5. In a horse shoe cork and carrier, a curved rib adapted to be disposed against the inner side of the horse shoe, there being openings in the curved rib, angular members having portions extending through the openings in the curved rib, the said portions of the angular members having depending flanges at the inner sides of the curved rib, the angular members having upwardly extending terminals normally disposed at the outer side of the horse shoe, there being openings in the terminals, and a strap disposed in the openings for the purpose specified.

6. In a horse shoe cork and carrier, a curved rib adapted to be disposed against the inner side of a horse shoe, there being openings in the curved rib, angular members having portions extending through the openings in the curved rib, the angular members having upwardly extending terminals normally disposed at the outer side

of the horse shoe, means for engaging the terminals for the purpose specified, flanges extending inwardly from the curved rib, and a pad secured to the flanges.

7. In a horse shoe cork and carrier, a cork normally disposed at the bottom of a horse's hoof, three members connected with the cork and extending upwardly one at the front and one at each side of the hoof, there being loops in the upper terminals of the said members and a strap normally disposed through the loops in the three members and then across the hoof of the horse shoe, from the member at one side of the horse's hoof to the member at the other side of the horse's hoof.

8. In a horse shoe cork and carrier, a curved plate with teeth and adapted to be disposed at the inner side of a horse shoe, there being openings in the front and sides of the plate, angular members disposed in the openings at the sides of the plate and adapted to extend upwardly at the outer sides of the horse shoe, an angular member disposed through the opening at the front of the plate and normally extending upwardly at the front of the horse shoe the last mentioned angular member being bent over to form a loop and extending down again with its terminal bent to form a tooth, there being openings in the angular members at the side of the plate and a strap disposed through the loop and the last mentioned openings.

9. In a horse shoe cork and carrier, a curved plate with teeth and adapted to be disposed at the inner side of a horse shoe, there being openings in the front and sides of the plate, angular members disposed in the openings at the sides of the plate and adapted to extend upwardly at the outer sides of the horse shoe, an angular member disposed through the opening at the front of the plate and normally extending upwardly at the front of the horse shoe the last mentioned angular member being bent over to form a loop and extending down again with its terminal bent to form a tooth, there being openings in the angular members at the sides of the plate, a strap disposed through loop and the last mentioned openings, and teeth on the first mentioned angular members.

In testimony whereof I have signed my name to this specification in the presence of two subscribing witnesses.

PHILIP NURSE.
